REFINING OF TAR ACID OIL

Everett Gorin and Martin B. Neuworth, Pittsburgh, Pa., assignors to Pittsburgh Consolidation Coal Company, Pittsburgh, Pa., a corporation of Pennsylvania

Application September 12, 1950, Serial No. 184,474

13 Claims. (Cl. 260—627)

1

This invention relates to the art of refining tar acid oil, and more particularly, to the separation and recovery of valuable tar acids from tar acid oil.

This application is a continuation-in-part of our copending application Serial Number 110,932, now abandoned, filed August 18, 1949, and assigned to the assignee of the present invention.

Primarily, this invention is directed to the recovery of tar acids from the tar produced in the low temperature carbonization of coal but the method of the invention is applicable to the tars produced in low, medium and high temperature carbonization operations on coals, lignite, oil shale, tar sands and similar bituminous materials, as well as to petroleum fractions containing tar acids and hydrogenation oils produced, for example, by the Bergius hydrogenation process or any other hydrogenation process.

Ordinarily tar acids are recovered from tar by a caustic process in which stoichiometric quantities of caustic react with the tar acids to produce water soluble tar acid salts which are separated from the remainder of the tar by decantation. Mineral acids are then employed to strip the tar acids from the tar acid salt solution. This caustic process has the virtue of recovering tar acids quantitatively in high purity but has an inherent disadvantage in that the reagents are consumed in the process. Where the tar contains only a small fraction of tar acids as is the case with tars resulting from high temperature coal carbonization, this disadvantage ordinarily can be disregarded.

In contrast to high temperature tars, the tars produced in the low temperature carbonization of coal or in coal hydrogenation processes contain considerable quantities of tar acids. For example, the distillate fractions of the tar obtained from the low temperature carbonization of Pittsburgh Seam coal contains 40 to 60 weight per cent of tar acids, 40 to 60 weight per cent of neutral oils and 0 to 5 weight per cent of tar bases, the exact composition being dependent upon the method by which the coal is carbonized, and the particular coal employed. For such tars, a tar acid recovery process is required which is less expensive and more efficient than those now available.

It is, therefore, the object of the present invention to provide a method for continuously recovering tar acids from tar acid oil.

A further object of this invention is to provide a method for recovering tar acids from tar acid oil by solvent extraction in a single continuous extraction column.

Another object of this invention is to provide a method for continuously separating tar acid oil into two fractions of which one is substantially

2

pure tar acids and the other substantially free of tar acids.

In accordance with our invention, we have discovered that tar acids can be efficiently recovered from tar acid oils by contacting tar acid oil with aqueous methanol and a low boiling paraffinic naphtha fraction in a continuous, countercurrent, center feed extraction column; provided certain critical limitations hereinafter set forth are observed.

10 In our new process, tar acids are dissolved selectively in the aqueous methanol while neutral oils are dissolved selectively in the naphtha. The use of aqueous methanol solution alone as a solvent for the recovery of tar acids is known, but such extractions are unsatisfactory because the neutral oils of the tar also are soluble to a limited extent in methanol with the result that the tar acids recovered are contaminated with neutral oils. Paraffinic naphtha alone is virtually useless to effect separation of the tar acids. Nevertheless, when aqueous methanol and paraffinic naphtha are employed in combination according to the present invention, high purity tar acids can be recovered from tar acid oils in high yields.

15 Specifically, a tar acid oil fraction preferably boiling within the range 160° to 300° C. is fed into the central portion of a continuous, countercurrent, double solvent, center feed extraction column. Aqueous methanol solution is fed into the top of said column and a low boiling, essentially paraffinic naphtha fraction is fed into the bottom of said column. The aqueous methanol passes downwardly through the column dissolving substantially all the tar acids and a small portion of neutral oils. The naphtha, being lighter than the aqueous methanol, passes upwardly through the column dissolving neutral oil. When the methanol solution of tar acids has reached the bottom of the column, the upward flowing naphtha will have removed substantially all of the small portion of dissolved neutral oil therefrom. The tar acids then may be readily recovered from the methanol in high purity by distillation; and similarly, the neutral oil may be recovered from the naphtha solution.

20 In the above process, it is necessary to employ aqueous methanol solution containing from 55 to 75 per cent by weight of methanol. In concentrations below 55 weight per cent, the methanol solution forms three phases which render the extraction column inoperable. Above 75 weight per cent concentrations, the methanol solution develops an affinity for neutral oils so that the resulting tar acids in the methanol extract are contaminated by the presence of neutral oils.

25 In general, for aqueous methanol solvent containing 55 to 75 per cent of methanol by weight, the recovery of tar acids increases and the purity

of the recovered tar acids decreases with higher methanol concentrations.

The process of this invention is further critically conditioned by the characteristics of the naphtha solvent. It must be essentially paraffinic in character. Such solvents may be obtained from the distillation of paraffinic petroleum stocks. Its boiling range should be 60 to 130° C., but preferably 60 to 100° C., in order to simplify the subsequent separation of the naphtha from the naphtha extract by distillation. And finally, the naphtha density should be less than 0.80 and preferably less than 0.75 to insure sufficient gravity difference between the two phases in the extraction column to effect a ready separation of the phases. The hexane cut of paraffinic naphtha combines all these critical properties and accordingly is preferred as the solvent in this invention.

The process of this invention may be practiced with either naphtha or aqueous methanol as the continuous phase in the phase contacting portion of the extraction column, but the former is preferred because of the greater efficiency of separation and recovery of the tar acids.

The distinguishing features of each type of operation will be described later in the specification. However, it should be pointed out here that the system employing aqueous methanol as the continuous phase was fully described in our copending application above referred to. Subsequent to the filing of that application, it was discovered that the use of naphtha as the continuous phase yields even better results and for that reason, the present application was prepared to more fully describe our invention.

For a better understanding of our invention, its objects and advantages, reference should be had to the accompanying drawings of which:

Figure 1 is a diagrammatic illustration of apparatus adapted to the practice of the preferred embodiment of this invention;

Figure 2 is a sectional drawing of an extraction column in which one modification of the present invention is practiced;

Figure 3 is a sectional drawing of an extraction column in which another modification of the present invention is practiced.

Referring to Figure 1, tar acid oil is pumped from a storage tank 10 continuously through a pipeline 12 into a continuous countercurrent double solvent center feed extraction column 14. The extraction column may be of any convenient design capable of providing a sufficient number of theoretical extraction stages to effect the desired separation of tar acids from the tar acid oil. A conventional packed tower may be used, for example, as well as a pierced plate column, a bubble plate column, or a column containing alternate zones of quiescence and turbulence. The exact point for introducing the tar acid oil is determined by the purity and extent of tar acid recovery desired. In general, however, the feed is preferably introduced at a point above the geometric center of any given extraction column.

The tar acid oil should be a fraction boiling in the range 160 to 300° C., but preferably boiling in the range 160 to 230° C. Since the lowest boiling tar acid, phenol, boils at 182° C., the minimum boiling point of the feed need not be less than 160° C. in order to assure recovery of substantially all low boiling acids contained in the original tar. On the other hand, since the highest boiling xyleneol boils at 225° C., the upper boiling point of the tar acid oil feed need not ex-

ceed 230° C. when recovery of only the low boiling tar acids is desired. Nevertheless, if it is desired to recover in addition certain higher alkyl phenols, dihydric phenols and bicyclic phenols present in the tar, the upper boiling point of the tar fraction need not exceed 300° C. to include the valuable higher molecular weight acids in the tar, nor should the upper boiling point exceed 300° C., because of the accompanying increased viscosity of the higher end point fractions.

Aqueous methanol solution is fed continuously from the aqueous methanol storage tank 16 through pipeline 18 into the top of the extraction column 14. Naphtha is fed continuously from the naphtha storage tank 20 through a pipeline 22 into the base of the extraction column 14.

Since the density of the aqueous methanol solution exceeds the density of the naphtha, the aqueous methanol solution descends through the column and dissolves tar acids while the lighter naphtha passes countercurrently upward through the column and dissolves neutral oils contained in the tar acid oil feed. Column throughput and contact time are dependent upon the column design. We found that surprisingly, there are no emulsification problems.

For every volume of tar acid oil feed, from 0.5 to 5.0 volumes of aqueous methanol and from 0.5 to 5.0 volumes of naphtha should be employed, whenever both high tar acid recovery and high tar acid purity are desired, and are, therefore, preferred. Moreover, for the same consideration, the ratio of aqueous methanol to naphtha should be controlled according to the solvent which is employed as the continuous phase, as will be pointed out.

It may be desirable to add a portion of the naphtha solvent to the tar acid oil feed, especially when a high end point (high viscosity) tar fraction is being treated. When such technique is employed, the naphtha so added should be considered as solvent for the purpose of determining solvent-to-feed and solvent-to-solvent ratios.

While the method of the present invention is relatively independent of the temperature at which the column is operated, it is preferred to operate the extraction column within the range of 60 to 120° F. The increased viscosity of tar acid oil at temperatures below this range introduces column operation difficulties, while the increasing solubility of neutral oils in the aqueous methanol solvent at higher temperatures decreases the yield and purity of the recovered tar acids. If necessary, the extraction column may be heated or cooled in any convenient manner.

Aqueous methanol extract, containing purified recovered tar acids, is withdrawn continuously from the extraction column 14 through a pipeline 24 and fed into a distillation column 26 for the separation of the methanol solvent from the water and purified tar acids both of which leave the still as bottoms through pipeline 28 and pass into a phase separation tank 30. Since the solubility of tar acids in water decreases with reduction in temperature, a cooler 32 may be placed in line 28 to cool the water and tar acids passing through line 28 and thereby to decrease the proportion of residual tar acids in the aqueous layer in phase separator 30. Purified tar acids, being virtually immiscible in water, separate from the aqueous layer in phase separator 30 and are withdrawn either continuously or intermittently as product through pipeline 34. The aqueous phase from the phase separator 30

is withdrawn through pipeline 36 and sent to the aqueous methanol storage tank 16 for recirculation.

Anhydrous methanol passes overhead from distillation tower 26 through pipeline 38 to a reflux condenser 40. Condensed anhydrous methanol leaves the reflux condenser 40 and passes through pipeline 42 to the aqueous methanol storage tank 16 for recirculation. A portion of the condensed methanol may be returned through pipeline 44 to the top of distillation column 26 as reflux.

It should be pointed out that in the preparation of the aqueous methanol solution in the storage tank 16, caution should be exercised if the solution is prepared and its composition regulated by specific gravity measurement. The recirculated methanol is saturated with naphtha and this fact must be considered in determining the specific gravity required to produce a solution containing 55 to 75 weight per cent methanol. Fresh methanol may be added to the aqueous methanol storage tank 16 from pipeline 46 to make up the necessary 55 to 75 weight per cent methanol solution.

Naphtha with dissolved neutral oil leaves the top of the extraction column 14 through pipeline 48 and passes to a distillation column 50 where the naphtha is separated from the neutral oil. Naphtha passes overhead from the still 50 through pipeline 52 and reflux condenser 54. A portion of the condensed naphtha may be circulated through pipeline 56 as reflux for the distillation column 50. The remainder of the naphtha is returned to the naphtha storage tank 20 through pipeline 58 for recirculation. Neutral oil leaves the still 50 as the bottom product through pipeline 60. A cooler 62 may be inserted in the exit pipeline 60 to cool the neutral oil product.

Now referring to Figure 2, the use of naphtha as the continuous phase will be discussed. Tar acid oil is fed through a pipeline 66 into the phase contacting zone 68 of an extraction column 70, suitable for the extraction operation of the present invention. Paraffinic naphtha is fed to column 70 through pipeline 72 and distributor 74 located between the phase contacting zone 68 and the bottom of the extraction column 70; aqueous methanol enters the column 70 through pipeline 76 and distributor 78. Naphtha extract is withdrawn overhead through pipeline 80; methanol extract leaves the column through pipeline 82.

The interface 84 between the naphtha and methanol phases is maintained at a point between the naphtha distributor 74 and the bottom of the extraction column 70 by regulating the rate of extract withdrawal through pipelines 80 and 82. Thus naphtha constitutes the continuous phase in the extract in column 70 above the interface 84.

Aqueous methanol, in the form of tiny globules, descends as a dispersed phase through the naphtha. In the upper portion of the contacting zone 68 (above the feed point of the tar acid oil), the aqueous methanol selectively dissolves tar acids and a small amount of neutral oil. As these methanol globules descend further, they contact and are dispersed in naphtha containing progressively decreasing amounts of dissolved neutral oil. Ultimately the dispersed methanol globules contact fresh, practically neutral oil free naphtha in a phase separation zone 86, dis-

posed below the phase contacting zone 68. These contacts between naphtha and dispersed aqueous methanol extract globules seem to strip the small amount of neutral oil from the globules and to transfer the stripped neutral oil to the naphtha phase, in which the neutral oil solubility is large as compared with the solubility of neutral oil in aqueous methanol. The phases separate at the bottom of the column 70 and the purified tar acids, dissolved in aqueous methanol, collect in the methanol phase zone 88 from which the extract is recovered. When naphtha is employed as the continuous phase, it is necessary in order to obtain high yields of a high quality product to regulate the solvent ratio so that the volume of aqueous methanol is from 0.25 to 4.0 times the volume of naphtha.

In the following Table I are tabulated results from a number of runs in which the continuous solvent phase was naphtha. A one-inch diameter, eight-feet long, center feed, countercurrent extraction column was employed and contained in its contacting zone 29 settling stages alternately disposed with 28 agitation stages. The feed stock to the extraction column was a tar acid oil having a boiling range of 160 to 230° C. The tar acid oil was obtained by fractional distillation of the liquid product from the low temperature carbonization of Pittsburgh Seam coal. The solvent naphtha was a hexane cut of naphtha boiling in the range 67 to 72° C. The column was operated at a temperature of 25° C.

60 1 60 percent methanol.

60 2 55 percent methanol.

60 3 20 percent methanol.

60 4 160-300° C. fraction of tar acid oil.

For a description of those systems in which aqueous methanol constitutes the continuous solvent phase, reference should be had to Figure 3, in which tar acid oil is fed through pipeline 96 to the phase contacting zone 98 of an extraction column 100, suitable for the extraction operation of this invention. Paraffinic naphtha is fed to the column 100 through pipeline 102 and distributor 104; aqueous methanol enters the column 100 through pipeline 106 and distributor 108, located between the phase contacting zone 98 and the top 109 of the extraction column 100. Naphtha extract is withdrawn

overhead through pipeline 110; methanol extract leaves the column through pipeline 112.

The interface 114 between the naphtha and methanol phases is maintained at a point between the methanol distributor 108 and the top of the extraction column 100, by regulating the rate of extract withdrawal. Thus the aqueous methanol constitutes the continuous phase in the extraction column 100 below the interface 114.

Naphtha, in the form of tiny globules, rises through the continuous methanol phase because of the difference in phase densities. The dispersed naphtha strips any dissolved neutral oil from the continuous aqueous methanol phase and also selectively dissolves the neutral oils from the feed stock. The phases separate in the upper portion of the column disposed above the phase contacting zone 98. Naphtha extract collects in the naphtha phase zone 116 above the aqueous methanol phase and is withdrawn through pipeline 110.

When aqueous methanol is employed as the continuous phase, it is necessary again in order to obtain high yields of a high purity product to regulate the solvent ratio so that the volume of aqueous methanol is from 0.5 to 2.0 times the volume of naphtha. It should also be emphasized again, however, that regardless of which solvent constitutes the continuous phase, from 0.5 to 5.0 volumes of aqueous methanol and from 0.5 to 5.0 volumes of naphtha should be employed for each volume of tar acid oil processed, if both high product purity and high yields are desired.

In the following Table II are tabulated the results of a series of runs in which the continuous solvent phase was aqueous methanol. A one-inch diameter, four-feet long center feed, countercurrent extraction column was employed and contained in its contacting zone 14 settling stages alternately disposed with 13 agitation stages. The feed stock as a tar acid oil fraction boiling in the range 160 to 300° C., obtained by fractional distillation of the tar from the low temperature carbonization of Pittsburgh Seam coal. The naphtha solvent was the hexane cut of petroleum naphtha, boiling in the range 67 to 72° C. Temperature of the column was 25° C.

TABLE II

¹60 percent methanol by weight.
²160-230° C. fraction of tar acid oil.

Thus it will be seen according to Table I and Table II that high purity tar acids can be recovered in high yield from tar acid oil by the process of this invention. Special attention is directed to run 3 of Table I and run A of Table II. These two runs show that where all other conditions are equivalent, the recovery and purity of tar acids is slightly but significantly better where naphtha constitutes the continuous phase than where aqueous methanol is the continuous phase.

Also it should be noted that a crude separation of the tar bases results from the practice of our invention. In general, about 60 per cent of the tar bases from the feed stock are removed with the naphtha extract. The balance of the tar bases remain in mixture with the tar acids. Furthermore, our new process removes most of the sulfur compounds which are usually and undesirably associated with tars and tar acids. In general, about 80 to 90 per cent of the sulfur compounds in the tar acid oil feed are removed in the naphtha extract, leaving only a trace of sulfur compounds to contaminate the purified tar acid product.

Run 5 of Table I indicates the effect of reducing the methanol content of the aqueous methanol solvent. A 55 weight per cent aqueous solution of methanol recovers only 85.3 per cent of the tar acids in the feed stock. The process of this invention with a 50 weight per cent aqueous solution of methanol is inoperable because of the formation of three phases in the extraction column. However, at some methanol concentration between 50 and 20 weight per cent, two phase operation is again effected but, as shown in run 6 of Table I, there is virtually no separation. (Less than one per cent of the tar acids in the feed stock are recovered.)

In summary, the process of our invention can be employed to separate tar acids from any tar acid oil, although it is especially desirable where the tar acid oil has a high content of tar acids, for example, 40 to 60 per cent. Both solvents employed can be recirculated through the process with a negligible loss per pass. Process costs are minimized further because the tar acid oil passes through the process without recirculation.

It may be desirable in certain cases to recover the tar acids in aqueous methanol solution for further processing in an aqueous methanol medium. For example, tar bases and corrosive contaminants could be removed from the tar acid extract while the tar acids remain dissolved in the aqueous methanol. Also the aqueous methanol solvent might be employed in a subsequent double solvent extraction process for the further purification and separation of the tar acids into monohydric phenols and dihydric phenols, for example.

Also the naphtha extract containing neutral oils may be recovered as it leaves the extraction column and processed directly by a double solvent extract process in which naphtha is employed as a solvent. Such a process for separation of the aromatic and saturated hydrocarbons of the neutral oil is described in United States Patent No. 2,633,448, entitled "Double Solvent Extraction of Oils" by M. B. Neuworth, dated March 31, 1953.

Ordinarily, however, the tar acids are desired in isolated form for use in resin manufacture. The method of our invention produces tar acids which are substantially free of contaminants that would impair properties of the product resins.

According to the provisions of the patent stat-

utes, we have explained the principle, preferred construction, and mode of operation of our invention and have illustrated and described what we now consider to represent its best embodiment. However, we desire to have it understood that, within the scope of the appended claims, the invention may be practiced otherwise than as specifically illustrated and described.

We claim:

1. A process for separating tar acids from a tar acid oil fraction which comprises the steps of feeding said tar acid oil to a vertical extraction zone at a point located between the ends thereof, feeding an aqueous methanol solution containing 55 to 75 weight per cent methanol and the balance water to the top of said extraction zone, feeding a second solvent consisting of a paraffinic naphtha fraction boiling within the range of 60° to 130° C. and having a density of less than 0.8 to the bottom of said extraction zone, passing said aqueous methanol solution and said naphtha fraction through said vertical extraction zone in countercurrent relation, and recovering aqueous methanol extract containing tar acids from the bottom of said vertical extraction zone.

2. The process of claim 1 in which the naphtha fraction is the continuous phase in said vertical extraction zone.

3. The process of claim 1 in which the aqueous methanol solution is the continuous phase in said vertical extraction zone.

4. The process of claim 1 in which methanol is separated from the aqueous methanol extract by distillation and recirculated in said extraction zone and that portion of the aqueous methanol extract remaining after removal of the methanol is separately recovered and the naphtha is separated from the naphtha extract by distillation and recirculated in said extraction zone and that portion of the naphtha extract remaining after the removal of the naphtha is separately recovered.

5. The process of claim 4 comprising the additional steps of recovering by phase separation the water from the water and tar acids which remain after the methanol has been distilled from the aqueous methanol extract, mixing said recovered water with said distilled methanol in such proportions that the resulting solution contains 55 to 75 weight per cent methanol, recirculating said aqueous methanol solution to the extraction zone and separately recovering the tar acids from said phase separation.

6. A process for separating tar acids from a tar acid oil fraction which comprises the steps of feeding said tar acid oil to a vertical extraction zone at point located between the ends thereof, feeding an aqueous methanol solution containing 55 to 75 weight per cent methanol and the balance water to the top of said vertical extraction zone, feeding a second solvent consisting of a paraffinic naphtha fraction boiling within the range of 60° to 130° C. and having a density less than 0.8 to the bottom of said vertical extraction zone, circulating said aqueous methanol solution downwardly and said naphtha fraction upwardly through said vertical extraction zone in countercurrent relation, regulating the rate of withdrawal of said solvents from said extraction zone so that the naphtha phase is the continuous phase, regulating the feed rate so that at least 0.5 and not more than 5.0 volumes of said aqueous

methanol solution and at least 0.5 and not more than 5.0 volumes of said naphtha are fed to said extraction zone for every volume of said tar acid oil fed to said extraction zone, further regulating the feed rates so that the volume of aqueous methanol solution is at least 0.25 but not more than 4.0 times the volume of naphtha fed to said extraction zone, and separately recovering the aqueous methanol extract and the naphtha extract.

7. The process of claim 6 in which the tar acid oil is a fraction boiling within the range of 160° to 300° C.

8. The process of claim 6 in which the naphtha solvent is a paraffinic naphtha boiling within the range of 60° to 100° C.

9. The process of claim 6 in which the naphtha solvent is a hexane cut of petroleum naphtha.

10. A process for separating tar acids from a tar acid oil which comprises the steps of feeding said tar acid oil to a vertical extraction zone at a point located between the ends thereof, feeding an aqueous methanol solution containing 55 to 75 weight per cent methanol and the balance water to the top of said vertical extraction zone, feeding a second solvent consisting of a paraffinic naphtha fraction boiling within the range of 60° to 130° C. and having a density less than 0.8 to the bottom of said extraction zone, circulating said aqueous methanol solution downwardly and said naphtha fraction upwardly through said vertical extraction zone in countercurrent relation, regulating the rate of withdrawal of said solvents from said extraction zone so that the aqueous methanol solution is the continuous phase, regulating the feed rate so that at least 0.5 and not more than 5.0 volumes of said aqueous methanol solution and at least 1.0 and not more than 5.0 volumes of said naphtha are fed to said extraction zone for every volume of said tar acid oil fed to said extraction zone, further regulating the feed rates so that the volume of aqueous methanol solution is at least 0.5 but not more than 2.0 times the volume of said naphtha fed to said extraction zone and separately recovering the aqueous methanol extract and the naphtha extract.

11. The process of claim 10 in which the tar acid oil is a fraction boiling within the range of 160° to 300° C.

12. The process of claim 10 in which the naphtha solvent is a paraffinic naphtha boiling within the range of 60° to 100° C.

13. The process of claim 10 in which the naphtha solvent is a hexane cut of petroleum naphtha.
